UNITED STATES PATENT OFFICE.

CHARLES L. POPE, OF KIMBERLY, IDAHO.

NECK-YOKE ATTACHMENT.

1,257,636.

Specification of Letters Patent. Patented Feb. 26, 1918.

Application filed July 2, 1917. Serial No. 178,299.

To all whom it may concern:

Be it known that I, CHARLES L. POPE, a citizen of Canada, residing at Kimberly, in the county of Twin Falls and State of Idaho, 5 have invented a new and useful Neck-Yoke Attachment, of which the following is a specification.

The present invention appertains to neck yokes, and aims to provide a novel and improved device for attaching a neck yoke to the tongue or pole of a wagon or other vehicle, permitting the yoke to be readily removed when the draft animals are unhitched, and preventing the reins from catching under the end of the tongue, as not infrequently happens with ordinary neck yoke attachments, and which sometimes results in runaways or accidents.

It is also the object of the invention to 20 provide a neck yoke attachment of simple and inexpensive structure which can be readily applied to various vehicles and removed therefrom, and which will be practicable and serviceable in use.

25 With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

30 The invention is illustrated in the accompanying drawing, wherein:

Figure 1 is a side elevation of the attachment.

40 Fig. 2 is a fragmental bottom view thereof.

Fig. 3 is a front end view.

The attachment embodies a sleeve or boot 1 constructed of suitable metal and adapted to be slipped onto the end portion of the 45 vehicle tongue or pole 2, which is preferably provided with a stop lug 3 for the abutment of the rear end of the sleeve thereagainst, the forward end of the sleeve being closed.

The forward end of the sleeve is provided 50 with an enlarged rounded portion 4 providing a bearing for the rolling contact of the intermediate portion of the neck yoke 5 thereon.

In order to attach the neck yoke to the

sleeve, the sleeve is provided with an upper 55 apertured lug 6 near its forward end to which one end of a short chain or flexible element 7 is anchored, the other end of said chain or flexible element being attached in any suitable manner to the upper portion of 60 the yoke 5 to prevent the forward movement of the yoke off of the sleeve or rounded portion 4 thereof. The chain 7 not only connects the yoke with the sleeve in rear of the yoke, but also prevents the reins from catching 65 between said yoke and sleeve.

The forward end of the sleeve is provided with a forwardly projecting arcuate lip 8 of arched form, having its widest portion at the top, and said lip diminishes in width toward its ends, the edges of the lip extending rearwardly and downwardly and vanishing into the end of the sleeve 4 at the lower portion thereof. This prevents the lines or reins catching under the lip 8, since when they are 70 pulled, they will be readily deflected forwardly out of engagement with the lip. The upper portion of the lip is provided with a pair of laterally spaced apertures 9, and there is a web or rib 10 between said apertures connecting the intermediate portion of the lip and forward end of the sleeve 1, said web being disposed vertically between the side portions of the lip, and strengthening the latter. Chain links 11 are engaged 75 through the apertures 9 and around the loop portions of the lip 8 formed by said apertures, and the links 11 are connected by eye bolts 12 or other attaching elements to the lower portion of the yoke 5. The links 11 80 in being engaged with the lip 8, will prevent the reins from catching thereunder, and when the yoke is pulled rearwardly by the backing of the draft animals, the links 11 will transmit the pull to the lip 8 and sleeve 95 1 for backing the vehicle. The links 11 also prevent the yoke from swinging too much out of its normal position, since said links diverge upwardly to the yoke to which their upper ends are attached.

The sleeve 1 is preferably provided with openings or slots 13 to lighten the same, and to prevent dirt and trash from accumulating therein.

The sleeve or boot 1 can be readily slipped onto the tongue when the animals are hitched to the wagon, but cannot become accidentally detached from the tongue, while the animals

are hitched up, although when the animals are unhitched the sleeve can be readily withdrawn.

Having thus described the invention, what is claimed as new is:

A device of the character described, embodying a sleeve to fit on the terminal of a tongue, the forward end of the sleeve having an outstanding arched lip provided with a pair of apertures in its upper portion, a web connecting said lip and forward end of the sleeve and located between said aper-

tures, a neck yoke resting on the sleeve, links engaging said lip in said apertures and attached to the yoke, and means connecting the yoke with the sleeve in rear of the yoke.

In testimony that I claim the foregoing as my own, I have hereto affixed my signature in the presence of two witnesses.

CHARLES L. POPE.
